UNITED STATES PATENT OFFICE

HENRY E. HOKE, OF HANOVER, PENNSYLVANIA

PEN CLIP

Application filed December 6, 1928. Serial No. 324,155.

This invention relates to a device for removably retaining a pen in a socket of a holder.

An object of the invention is the provision of a simple and efficient resilient member formed of a single strip of resilient material which may be inserted within the socket of a pen holder for retaining a pen in the socket, the device being so constructed that pressure upon the projecting portion of the retaining device will readily release the pen from the socket.

A further object of the invention is the provision of a device for retaining a pen in a socket of a holder and formed of a single strip of resilient material having one end bent to provide a U-shaped member adapted to frictionally engage the walls of the socket of a pen holder, one leg of the U-shaped member being extended sufficiently to engage the pen and frictionally clamp the inner end of the pen to the wall of the socket.

A further object of the invention is the provision of a device for retaining a pen in the socket of a holder, the device being formed of resilient material and having a U-shaped member frictionally engaging the walls of the socket with the free end of one leg being pointed for aiding in retaining the U-shaped member against accidental displacement from the socket, the other leg being extended to form a clamp for maintaining the pen against movement, the free end of the extension being disposed externally of the socket and manually operable for releasing the pen or for facilitating the insertion of the pen in the socket.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

Figure 1 is a vertical section of the preferred form of the invention.

Figure 2 is a vertical section of a modified form of the retaining clip.

Figure 3 is a vertical section of a pen holder showing a further modified form of the invention.

Figure 4 is a view in perspective of the clip illustrated in Figure 1.

Figure 5 is a view in perspective of the clip mounted in the holder as shown in Figure 2.

Figure 6 is a view in perspective of the clip illustrated in Figure 3.

Figure 7 is a view in perspective of a pen holder showing a modified form of the clip.

Figure 8 is a vertical section of the holder shown in Figure 7.

Figure 9 is a view in perspective of the clip disclosed in Figures 7 and 8.

Referring more particularly to the drawings, 10 designates a pen holder formed of any suitable material and having at its outer end a cylindrical socket 11 which opens at 12 through one end of the holder 10. A metal protecting sleeve 13 is secured to the end of the holder 10 and has an inturned flange 14 embracing the outer end of the holder and terminating at its inner edge in alignment with the wall of the socket 11. Mounted within the socket is a clip formed of resilient material such as spring steel or brass.

The clip has a U-shaped member 30 having a leg 31 provided with a pointed end 32 and a leg 33 substantially parallel to the leg 31. Said leg has an extension as shown at 34 bent outwardly at 35 for engaging the body 23 of the pen 22.

The upper end of the leg is bent at 36 and at a right angle to the extension 34 and then bent inwardly upon itself as at 37 where the same is expanded to form an annular member 38 having an opening 39 through which the pen 22 is inserted. The annular member 38 has a lip 40 shaped to conform to the curvature of the pen 22 and to be received by the inner surface of the pen.

This clip is inserted in the socket 11 with the point 32 engaging the wall of the socket and the outer surface adjacent the lower end of the leg 33 engaging the oppositely disposed portion of the wall of the socket.

When it is desired to remove the pen 22 from the socket, it is only necessary to press upon the outer free end of the annular member 38 whereby the portion 34 will be moved away from the pen 22 so that the pen will fall by gravity from the socket.

The clip shown in Figures 2 and 5 comprises a leg 41 of a U-shaped member 42 with the outer free end 43 of the leg 44 being pointed to engage a point of the wall surface of the socket 11. The leg 41 is substantially straight and extended upwardly where it is bent as shown at 45 to provide a finger piece 46. Arms 47 extend outwardly from the finger piece and downwardly as shown at 48 with the members 48 being located outwardly or spaced from the surface of the outer end of the holder 10 so that when the pen holder is placed upon the desk, it will be supported in spaced relation from the desk on the members 48. This is also true of the clip shown in Figure 4 which has a substantially flat portion 49 supporting the pen holder. When it is desired to remove the pen from the socket 11, it is only necessary to press upon the members 48 whereby the leg 41 will be moved out of contact with the body 23 of the pen 22. The same operation is effected when it is desired to insert the pen into the holder.

A modified form of the clip is shown in Figures 3 and 6 and in which a U-shaped member 50 has one leg 51 provided with a pointed end 52, while the other leg 53 has an extension 54 disposed at an angle to the leg 53. The extension of the pair of arms 55 and 56 is disposed at right angles to a plane passing through the member 54. The arm 55 is bent inwardly at 57 and then at 58 while the arm 56 embraces the extension of the arm 55 and has a portion 57 located outwardly of the bent portion 57.

This clip is inserted within the socket 11 shown in Figure 3 and the pen is inserted through the passage formed by the arm 55 and its extensions 57 and 58. Due to the resiliency of the U-shaped member 50, the arm 54 will force the head or portion 60 in clamping relation with the pen for maintaining the pen in position.

When it is desired to remove the pen or to insert a pen in the socket, it is only necessary to exert a slight pressure on the member 57 whence the leg 54 will be moved inwardly and permit the pen 22 to fall from the socket 11, or when the pen is being replaced, it may be inserted through the passage just described when pressure has been removed from the member 57. The resilience of the material will force the head 60 into clamping relation with the pen.

In the form shown in Figures 7, 8 and 9, it will be seen that the clip is made of resilient wire having a substantially annular member 70 to receive the pen with the bridging portion 71 acting as a rest or support for

the pen holder on a desk. The free ends of the member 70 are bent inwardly as at 72 and then downwardly to provide a pair of spaced legs 73 which are bent outwardly and upwardly to form a U-shaped member 74 with the free ends 75 of the legs 76 being pointed to engage a portion of the surface of the socket 11.

The clip is inserted within the socket and moved inwardly until the annular member 70 rests upon the outer end of the socket. Pressure upon the bridging portion 71 will move the legs 73 outwardly from the wall of the socket and either permit the removal or insertion of the pen 22. The legs are provided with shoulders 77 which engage the inner face of the pen 22, and aids in clamping the pen in position.

I claim:

1. A device for removably retaining a pen in the socket of a holder comprising a metal member formed of resilient material and having means received within the socket for frictionally engaging the walls of said socket, an arm projecting from said friction means and extending at right angles to the axis of the holder and across the open end of the socket and provided with a passage through which is adapted to be inserted the shank of a pen, said arm adapted to be manipulated across the outer end of the holder for releasing the pen point.

2. A device for removably retaining a pen in the socket of a holder comprising a metal member formed of resilient material having a U-shaped member received within the socket, one leg of the U-shaped member projecting beyond the open end of the socket and having a finger piece connected integrally with the last-mentioned leg to provide means for manipulating the leg to release the pen, said finger piece having means upon opposite sides of the leg for engagement with the shank of the pen for aiding in clamping the shank against the wall of the socket.

3. A device for removably retaining a pen in the socket of a holder comprising a metal member formed of resilient material and having a U-shaped member received within the socket for frictionally engaging the walls of the socket, one leg of the U-shaped member being extended and adapted to engage the shank of the pen for maintaining said pen in the socket, the free end of the extension being formed integrally with the leg and extending at a right angle to the extension to provide not only a finger piece actuating the extension to release the pen but to provide a rest for supporting the pen on a horizontal surface, said angular portion having an opening through which the pen is adapted to be inserted.

HENRY E. HOKE.
